DESIGN FOR A VEHICLE HEATER CASING OR THE LIKE

Carl E. Meyerhoefer, Brooklyn, N. Y., assignor to
E. A. Laboratories, Inc., Brooklyn, N. Y., a cor-
poration of New York

Application July 20, 1936, Serial No. 63,938

Term of patent 14 years

To all whom it may concern:

Be it known that I, Carl E. Meyerhoefer, a citizen of Germany, who has declared his intention of becoming a citizen of the United States, residing in Brooklyn, Kings County, New York, have invented a new, original, and ornamental Design for a Vehicle Heater Casing or the like, of which the following is a specification, reference being had to the accompanying drawing forming part thereof.

Figure 1 is a front elevation, and Figure 2 is a side elevation of a vehicle heater casing or the like, showing my new design.

I claim:

The ornamental design for a vehicle heater casing or the like, as shown.

CARL E. MEYERHOEFER.
